HORIZONTAL SLIDING DOOR FOR PRESSURE VESSELS

Henry J. Plegza, Clarence, N.Y., assignor to Welding and
Steel Fabrication Co., Inc., Tonawanda, N.Y.

Filed Nov. 4, 1971, Ser. No. 195,891

Term of patent 14 years

Int. Cl. D15—99

U.S. Cl. D55—1 R

FIG. 1 is a front perspective view of the horizontal sliding door for pressure vessels;

FIG. 2 is a front perspective view thereof with an element in an alternative position;

FIG. 3 is a top plan view thereof, as shown in FIG. 2; FIGS. 4 and 5 are end views thereof, as shown in FIG. 2; and

FIG. 6 is a rear elevational view thereof, as shown in FIG. 1.

The broken line disclosure of FIG. 1 is for illustrative purposes only and forms no part of the claimed design.

I claim:

The ornamental design for a horizontal sliding door for pressure vessels, as shown and described.
